UNITED STATES PATENT OFFICE.

EDWARD G. BERNA, OF ROCHESTER, NEW YORK.

APPLE-FACING DEVICE.

1,413,957.

Specification of Letters Patent. Patented Apr. 25, 1922.

Application filed April 20, 1921. Serial No. 462,947.

To all whom it may concern:

Be it known that I, EDWARD G. BERNA, a citizen of the United States, residing at Rochester, in the county of Monroe and 5 State of New York, have invented certain new and useful Improvements in Apple-Facing Devices, of which the following is a specification.

The object of this invention is to provide 10 a new and improved form of device with which one or more layers of apples can be faced in a barrel.

This and other objects of this invention 15 will be fully illustrated in the drawing, described in the specification and pointed out in the claims at the end thereof.

In the accompanying drawing:

Figure 1 is a perspective view of the apple 20 facing device.

Figure 2 is a perspective view of the pad used in connection with the apple facing device to support the apples in the device while it is being filled and located in the barrel.

Figure 3 is a vertical sectional view of a 25 barrel with the apple facing device placed therein ready to face a layer of apples in the barrel.

Figure 4 is a perspective view of a modified form of apple facing device.

In the several figures of the drawing like reference numerals indicate like parts.

Apples are usually faced in barrels so that when the barrel is opened one or more of 30 the top layers of apples present a good appearance and show the grade and kind of apples that are contained in the barrel. For this purpose it has been customary to carefully lay and place the apples of the first

40 layer in such a way that when the filled barrel is opened this first layer of apples is located at the top thereof. In order to face a layer of apples it has heretofore been necessary to handle each of the apples and 45 place it carefully into the barrel. This layer is usually put on the bottom of the empty barrel which end is marked the top when the barrel is filled so that it will be opened on the end in which the apples have been 50 faced and will make the best appearance.

In my present invention the facing of one or more layers is simplified and is done outside of the barrel so that a whole layer of apples already faced can be placed and located in the barrel at one time.

This invention comprises the cylindrical

shell 1 made up of sheet metal to which a pair of handles 2 and 3 are attached at the top at points diametrically opposite each other. Both ends of this shell are open and 60 the lower edge thereof is provided with four notches 4, 5, 6 and 7 which are used for a purpose that will presently appear.

A strap 9 made preferably of leather is 65 adapted to span the lower end of the cylindrical shell 1. This strap is fastened to the shell by placing the middle portion of the strap in back of the handle 3 and over the portion of the upper edge of the shell which is spanned by the handle 3. Each side of 70 the strap is then passed down on the outside of the shell to the notches 6 and 7 respectively. From these notches the ends of the leather strips are crossed over to the notches 4 and 5 diagonally opposite the notches 6 75 and 7, and then passed up on the side of the cylindrical shell to a pin 8 carried on the outside of the handle 2. Each end of the strap is provided with a hole which is adapted to be engaged by the pin 8 and in so 80 doing hold the ends of the strap in place on the handle 2. The ends of the strap in crossing from one side of the shell to the other, cross each other and form cross members on which the pad 10 is adapted to be 85 supported.

The pad 10 is preferably made up of corrugated card board with a smooth surface on one or both sides thereof. The pad 10 is placed on top of the strap 9 spacing the 90 lower end of the cylindrical shell to form a bottom therefor. A layer of apples is then placed on top of the pad 10 and each apple of this layer is placed with its blow end at the top.

The shell with the layer of apples is then placed into the bottom of the barrel 11 as indicated in section in Figure 3. The ends of the strap 9 are then disengaged from the pin 8 on the handle 2 after which the portion of the strap passing over the back of the handle 3 is taken hold of and pulled up therefrom. This action pulls the ends of the strap from under the pad 10 which then drops to the bottom of the barrel with the 105 layer of apples on top of it.

After the strap 9 is withdrawn the cylindrical shell 1 is no longer attached to the pad supporting the layer of apples so that the shell can be withdrawn as well, leaving 110 the apples and pad alone in place on the bottom of the barrel. The barrel with the

layer of faced apples at the bottom is then filled with other apples without placing them in any particular position. After the barrel is filled it is closed with a head ready 5 for shipment.

In opening the barrel instead of opening the head with which the barrel has been closed after being filled with apples, the other head which formed the bottom of the 10 barrel when the barrel was being filled is opened. In other words the barrel is placed up side down when being opened. In this way the pad 10 is exposed first when the barrel is opened and when the pad is removed 15 the layer of apples that had been faced therein is exposed for the inspection of the grade and kind of apples contained therein in a particularly pleasing presentation of each apple to the eyes of the observer.

In the modification shown in Fig. 4, the cylindrical shell is provided with a bail 11 instead of the handles 2 and 3 and the notches are replaced by the slots 12.

25 I claim:

1. In a device for facing apples, the combination of a cylindrical shell, removable cross members temporarily attached to the open bottom of said cylindrical shell, said 30 cross members being adapted to be withdrawn from the bottom of said shell at one side thereof.

2. In a device for facing apples, the combination of a cylindrical shell, a strap fastened to the side of said shell and spanning 35 the open end of said shell, said strap being adapted to be released from the sides of said

shell to allow the withdrawal thereof from the bottom of the cylindrical shell.

3. In a device for facing apples, the combination of a cylindrical shell, a strap spanning an open end of said cylindrical shell, the middle portion of said strap being held in place on said cylindrical shell against movement in one direction, the ends of said 45 strap being attached to the opposite side of said shell against movement in either direction, said strap being adapted to be withdrawn from the open end of said shell by disengaging the ends of said strap from one 50 side of said shell to allow the withdrawal thereof from the other side of said shell.

4. In a device for facing apples, the combination of a cylindrical shell, a pair of handles provided at the top of said shell, said shell having notches provided in the bottom edge, a strap engaging said notches and spanning the open end of said shell, means to temporarily fasten the ends of said strap to one of said handles.

5. In a device for facing apples, the combination of a cylindrical shell, fastening means at two diametrically opposite points on the outside of said shell, the bottom edge of said shell having notches provided therein, a flexible strap fastened to said fastening means and passing through said notches from diametrically opposite points across an open end of said shell to form a support at one end of the shell, said strap being adapted to have a pad resting thereon on the inside of said shell.

In testimony whereof I affix my signature.

EDWARD G. BERNA.
